(57) **CLAIM**

The ornamental design for a ultrasonic/electromagnetic pest repeller, as shown and described.

DESCRIPTION

FIG. 1 is a perspective view of a ultrasonic/electromagnetic pest repeller, showing our new design;

FIG. 2 is a front view of the ultrasonic/electromagnetic pest repeller shown in FIG. 1;

FIG. 3 is a left side view of the ultrasonic/electromagnetic pest repeller shown in FIG. 1;

FIG. 4 is a rear view of the ultrasonic/electromagnetic pest repeller shown in FIG. 1;

FIG. 5 is a right side view of the ultrasonic/electromagnetic pest repeller shown in FIG. 1;

FIG. 6 is a top view of the ultrasonic/electromagnetic pest repeller shown in FIG. 1; and,

FIG. 7 is a bottom view of the ultrasonic/electromagnetic pest repeller shown in FIG. 1.

The broken line showing of environment in the drawings is for illustrative purposes only and forms no part of the claimed design.
